UNITED STATES PATENT OFFICE.

ROBERT C. ALEXANDER, OF SHREVEPORT, LOUISIANA.

IRONING-BOARD.

1,318,195.

Specification of Letters Patent.

Patented Oct. 7, 1919.

Application filed March 12, 1919. Serial No. 282,059.

To all whom it may concern:

Be it known that I, ROBERT C. ALEXANDER, a citizen of the United States, residing at Shreveport, in the county of Caddo and 5 State of Louisiana, have invented certain new and useful Improvements in Ironing- Boards; and I do hereby declare the following to be a full, clear, and exact description of the invention, such as will enable others skilled in the art to which it appertains to 10 make and use the same.

This invention relates to an ironing table and particularly to a closely folding construction thereof.

15 The invention has for an object to provide a novel and improved construction of table comprising crossed front and rear legs pivoted together and foldably connected to the board, and a stay for connecting the 20 legs and adapted to closely nest with the other parts when they are in folded position.

With the foregoing and other objects in view which will be apparent as the description proceeds, the invention resides in the construction and arrangement of parts hereinafter described and claimed, it being understood that changes can be made within the scope of what is claimed without 25 departing from the spirit of the invention.

The invention is illustrated in the accompanying drawings, wherein:—

Figure 1 is a side elevation of the table in erect position;

35 Fig. 2 is a side elevation of the same folded;

Fig. 3 is a bottom plan view of the folded table; and

40 Fig. 4 is a cross section of line 4—4 of Fig. 3.

The ironing board 10 may be of any desired construction or configuration and is provided upon its under face with a pair of longitudinally extending cleats or ribs 45 11 each having therein an elongated slot 12. The under side of the board is also provided at the rear with depending lugs 13 to the inner sides of which the upper ends of the parallel front legs 14 are secured by means 50 of the pivots 15. These legs are also pivotally connected to the rear legs 16 by means of the pivot bolts 17. The rear legs 16 are parallel and disposed at the opposite sides 55 of the ribs 11 between the legs 14 while the upper ends thereof are connected together by a bolt or tie member 18 slidably mounted

in the elongated slots 12 of the ribs. The front legs 14 are at the outer sides of the rear legs, said rear legs being adapted to fold next to the ribs 11 with the legs 14 60 outside of the rear legs.

For the purpose of added stability these rear legs are provided with truss braces 19 extending downwardly at an angle therefrom at the outer sides of the legs 14 and 65 secured at their upper ends by the pivot bolts 17. The braces 19 are connected near their base by a cross bar 20 which is secured to the lower end of the rear legs 16.

For the purpose of adjusting and retaining the board at different elevations a stay 21 is provided which may be of any desired material, preferably of metal rod, and is pivoted at its ends, as at 22, in the brace or truss members 19 of the legs 16. This stay 70 21 is of U-shape and its yoke 23 is provided with engaging loops 24 to seat over the front legs 14. For this purpose these legs are provided with a series of notches or recesses 25 in their upper edges which permit the vertical adjustment of the table by engaging the connecting stay in the various notches. The front legs are also provided with a recess 26 adapted to receive the loops 25 of the stay 21 when the parts are in 80 folded position and when in this position the dropped or offset portion of the yoke 23 fits astride and around ribs 11 below the under side of the board. The longitudinal side members of the stay 21 extend across 90 the outer sides of the legs 14, so that the loops 24 can engage over said legs, with the offset portion of the yoke depending between said legs to provide an effective relation of said legs and stay.

95 The folding and unfolding movement of the several parts will be apparent from the foregoing description, and it will be seen that when extended the legs are firmly braced by the truss members 19 against side 100 movement and held in their extended and adjusted position by the stay 21, while when folded the parts are adapted to closely seat against the board at the opposite side of the ribs thus effecting a compact flat structure 105 very convenient for storage or transportation. The brace members produce a tripod effect thus securing rigidity of the table, and when erected for use a large portion of the board is extended beyond the rear leg pivot 110 18 so as to render it convenient for the introduction of articles over the free end.

of the board. It will also be observed that when the table is erected the parts automatically assume their proper position and the stay 21 falls by gravity into the proper 5 notch or recess to establish the desired elevation of the board.

This invention presents a very simple effective and economically constructed form 10 of folding ironing table particularly adapted for domestic use, while a special construction and configuration of the several parts has been herein shown the invention is not 15 specifically confined thereto and is defined by what is now claimed.

What I claim is:—

An ironing board having upon its under 15 face a longitudinally extending slotted rib, front legs pivotally connected to the under

side of said board to fold next to the rib, rear legs crossing and pivotally connected 20 to the outer sides of said front legs and having their upper ends slidably connected through said slot, truss members extending downwardly from said pivotal connections at the outer sides of the front legs, a cross 25 bar connecting the truss members and the lower ends of the rear legs, and a stay extending from the truss members and adjustably connected to the front legs.

In testimony whereof I have signed my 30 name to this specification in the presence of two subscribing witnesses.

ROBERT C. ALEXANDER.
